UNITED STATES PATENT OFFICE

HAROLD G. EYNON AND WALTER J. KINDELMAN, OF PHILADELPHIA, PENNSYLVANIA,
ASSIGNORS TO INDUSTRIAL DEVELOPERS, INC., OF PHILADELPHIA, PENNSYLVANIA,
A CORPORATION OF DELAWARE

METAL SEAL FOR PAPER BAGS

Application filed August 7, 1929. Serial No. 384,098.

Our invention relates to a flexible metal tie for use at the open end of a paper bag in order to effect a folding closure of the bag, the metal tie folding with the paper and by reason of its stiffness holding the paper in its folded position. Rolling and folding are viewed as substantially the same for present purposes.

A purpose of our invention is to provide a metal tie of the character indicated that will be easy and inexpensive to manufacture and to apply to a bag by machinery or by hand either during or subsequent to the manufacture of the bag and adapted to the needs of service.

A further purpose is to provide a metal tie of the character indicated that will always be contained within the dimensions of the bag.

A further purpose is to provide a bag with a metal tie of the character indicated that will be contained within the width of and on the outside of one of the long sides of the bag.

A further purpose is to provide a metal tie of the character indicated adapted to easy machine or hand sift-proof closure and after closure to hand opening and subsequent sift-proof reclosure by machine or by hand equally well at any point along a range of closure depending upon a variation in the volume of material inside the bag.

A further purpose is to provide a type of metal tie that can be readily opened and closed without rupture of the bag structure or tie cover at either top or bottom of the tie.

A further purpose is to provide metal tie upon the outside of the long side of a bag in which the tie presents side portions parallel to the edges of the long side and one or more cross portions preferably at top and bottom for lessening the stress upon the material of the bag when folding and unfolding the closure.

We have elected to show a few only of the many different forms of our invention, selecting forms that are practical and efficient in operation and which well illustrate the principles involved.

Figure 1 shows a front elevation of a folded bag of a type well adapted to be closed by the use of structure embodying our invention.

Figure 2 is a section taken upon the line 55 2-2 of Figure 1.

Figure 3 shows one form of metal tie adapted to be used upon the bag of Figure 1 in accord with our invention.

Figs. 3a-3g are modifications of the metal 60 tie that may be used.

Figure 4 shows a cover sheet for use in holding the tie of Figure 3 to place upon the bag of Figure 1.

Figure 5 is a fragmentary front elevation 65 corresponding generally to a portion of Figure 1 but showing the tie and its cover both fastened to place, the cover being partially broken away to disclose the tie.

Figure 6 is a section taken upon the line 70 6-6 of Figure 5.

Figure 7 is a view corresponding generally to Figure 5 but showing a somewhat different form from that of Figure 5.

Figure 8 is a section taken upon the line 75 8-8 of Figure 7.

Figure 9 is a section corresponding to Figure 8 but showing the bag as having its long sides spaced apart instead of being relatively close together as in Figure 8.

Figure 10 is a fragmentary side elevation 80 partly sectioned showing a bag after it has been filled with the upper edges of the long sides presented together preparatory to making a folding seal.

Figures 11, 12 and 13 are views corresponding generally to Figure 10 but showing progressive stages of folding closure, the bag being shown closed in Figure 13.

Figure 14 is a view corresponding generally 90 to Figure 13 but showing a lesser volume of material inside the bag than is shown in Figure 13, for example the bag of Figure 13 initially perhaps containing unground coffee beans while the bag shown in Figure 14 contains the same coffee ground and therefore of somewhat less volume than in Figure 13.

Like numerals refer to like parts in all figures.

Describing in illustration and not in limitation and referring to the drawings:—

Our flexible metal tie for use in closing bags is believed to have perhaps its widest application with bag filling and closing machines but is also very convenient for closing bags by hand and should therefore also find a wide application with grocers and others who have miscellaneous paper bags to fill and close.

While the tie is for use with any suitable type of bags it is perhaps used most advantageously with paper bags that have a rectangular contour and we have for this reason illustrated it applied to this type of bag.

The illustrated bag may be lined or unlined. In most of the illustrations it is of the kind used for packing coffee, double, including an inside lining 20, and an outside bag 21, the lining being usually of wax paper, impervious to moisture. In Figure 9 it is unlined.

The bags have short and long sides that extend upwardly from a rectangular bottom 22 and therefore give the bag a rectangular transverse section when extended.

The bags are creased for folding flat when empty, the short sides creased longitudinally at 23 and turned inward between the long sides which are pressed together upon the inwardly folded short sides, each short side then having one-half of its width against one of the long sides and the other half of its width against the other long side.

One of the long sides of the bag is cut lower than the other at 24, Figures 1 and 5 in order to make the bag more easy to open and we preferably apply our metal tie 25 to the long side that is cut away, applying it across the outside and the top edge (Figures 5 and 7).

We use a tie that will be wholly contained within the lateral dimensions of the bag whether the bag be empty or be filled and closed. We fasten the tie to place by a sticker 26 which has part of its area glued to the outside of the bag and another part of its area covering the tie.

When a bag has been filled for closure the ends of the bag extend upwardly a considerable distance beyond the filling material, a distance sufficient for a folding closure. The closure can be effected by rolling. It is our intention to include "roll" or "rolling" within the meaning here of the words "fold" or "folding".

The metal tie 25 may have widely variant forms of which a few only are shown in Figures 3-3g. It is illustrated as formed of wire, plain, flattened to give extra width or bent upon itself for the same purpose, for example, as in Figures 3a, 3b or 3d, and as cut from sheets of metal, as in Figures 3, 3e, 3f or 3g, and as cut from foraminous material as in Figure 3c.

In Figure 3 the metal member 25 is rectangular frame, cut away in the middle and having corners, preferably rounded.

Usually the side portions 27 of the frame should be wider than the transverse portions 28.

The side portions fold during the folding closure of the bag and should have such width as is needed to provide adequate stiffness for maintaining the fold and for avoiding undue tendency for the ends of the side portions to tear the material of the bag during folding or unfolding. The transverse portions 28 are preferably located at the ends of the side portions in that when thus located they greatly lessen the tendency for the ends of the side portions to tear the material of the bag during folding or unfolding.

The sides may be of round wire, for example, as in Figures 3b and 3d, with transverse portions of spaced wires as in Figure 3b or with flattened transverse portions as in Figure 3d.

The forms offer different advantages. In the tie shown in Figure 3 the side portions 27 are connected at top and bottom with the transverse portions 28 and the cross pieces at top and bottom are in positions to prevent the ends of the side pieces from exerting undue pressure against the paper during folding or unfolding, thereby preventing rupture of the paper at these ends.

In Figure 5 we make the metal closure member 25 of width less than the width of the long side of the bag, thus leaving marginal spaces 29 outside the outer edges of the tie for engagement and gluing to the cover sheet 26.

In Figure 7 we give the metal tie the width of the long side of the bag and hold the member to place by the cover sheet either by using a sheet also of the width of the bag extending, however, suitable marginal distance above and below the tie, merely gluing the sheet at the upper and lower margins 30 and 31 and over the interior 32 of the frame or more desirably by using a sheet wider than the bag extending as indicated at 33, Figure 9, to overlap and glue to the short sides of the bag.

In Figure 3e the insert comprises a U member having vertical sides and a close connection at the bottom corresponding generally to the form of Figure 3 without the top cross portion.

The wire tie can be adapted to any of the shapes desirable, flattening or doubling or reinforcing parts which require extra strength or a different distribution of the metal or of the stiffening character. Figures 3a, 3b and 3d are not intended to cover the subject, but to suggest forms merely.

Figure 3f shows a form like Figure 3e except that the cross portion between the parallel sides is intermediate the length of the

sides instead of near the bottom thereof, the metal member comprising an **H**.

In Figure 3g the cross connection between the side portions is diagonal instead of perpendicular to the sides, the final form comprising an **N**.

It will be understood that the different forms of closure member shown are few only of many others, all of which may be used interchangeably according to circumstance or difference in taste or whim.

When the bag has been filled the long sides are presented together along the upper edges forming a compressed strip 34 just above the upper edge of the insert member 26 in the position shown in Figure 10, the short sides at their upper ends being folded in between the long sides.

The strip 34 at the top of the bag now includes the two thicknesses of bag and lining which is folded down to successive positions indicated in Figures 11, 12 and 13, Figure 13 showing the bag in its position of final closure and the stiffness of the metal insert holding the fold closed.

It will be understood that the bag may be opened and again sealed by closure upon a different volume of material, either by a housewife or a grocer. For example the grocer may receive the bags filled with coffee beans and open the bag, grind the coffee, pour it into the bag and reseal the bag.

When the ground coffee is put back in the bag, the bag will not be as full as with the unground coffee beans and in effecting closure the folding is therefore continued to some little distance further than when the bag contained the beans. If the tie extends far enough down into the top the seal will be equally efficient at both of the different heights.

It will be evident that the side bars alone if permanently fastened to the outside of the bag even without any direct, transverse or other cross connection would still be valuable in the sealing of the bag as the ends of the seal will be taken care of by the side bars folded with them; though lacking part of the benefit of our invention this would still be capable of giving comparatively good results.

It will be evident also that various means of permanent attachment of the tie (or separated tie members) can be used whereby the tie is anchored sufficiently with respect to the bag so as reliably to fold with it. We have illustrated the best form of attachment known to us, as required by the statute, in the form of stickers intended to pass over all or any desired or required part of the tie (or tie elements) so as to hold the tie to the bag; but it is not our intention to suggest that stickers must be used for this purpose nor that where they are used other forms of attachment may not be used as accessories to the stickers.

It will be evident that where permanent fastening means is used it is not intended to imply that the fastening means must be incapable of separation from the bag nor that it be a tie member separate from the tie itself. For example, this language would be satisfied by use of such devices as clips 35 about or prongs (36) through the paper with or without supplementary attachment means. The clips or prongs would in that event be preferably integral with the ties as in Figures 3e and 3f. The structures of these figures could be used without the clips or prongs if desired, with stickers or other means of attachment.

The clips could pinch tightly against the infolded sides of the bag near the open ends of the bag, much in the position of the paper 33 in Figure 9 when glued, or pinch over the top of the bag but the prongs would pass through the bag.

In view of our invention and disclosure variations and modifications to meet individual whim or particular need will doubtless become evident to others skilled in the art, to obtain all or part of the benefits of our invention without copying the structure shown, and we, therefore, claim all such in so far as they fall within the reasonable spirit and scope of our invention.

Having thus described our invention, what we claim as new and desire to secure by Letters Patent is:

1. A bag, a closure tie secured permanently to the outside of the bag and comprising a metal tie having side portions parallel to and near the bag edges and a transverse connection between the side portions.

2. A bag, a closure secured permanently to the outside of the bag and comprising a metal tie having side portions parallel to and near the bag edges and a transverse connection between the side portions at the bottom ends thereof.

3. A bag, a closure secured permanently to the outside of the bag and comprising a metal tie having side portions parallel to and near the bag edges and a transverse connection between the side portions at the top ends thereof.

4. A bag, a metal tie secured to the outside of the bag and comprising a rectangular sheet having relatively wide sides and narrow ends, the sides located parallel to and near the bag edges near the open end of the bag and folding with the bag to a position contained within the bag dimensions.

5. A bag, a metal tie on the outside of the bag near the open end thereof having side portions and a transverse connection therebetween, the side portions being located parallel and near the bag edges, and a sticker having margin portions glued to the outside of the bag and covering the tie intermediate the margins.

6. A bag, a metal tie on the outside of the bag near the open end thereof having side portions and a transverse connection therebetween, the side portions being located parallel and near the bag edges, and a sticker having margin portions along the bag edges beyond the tie edges and glued to the outside of the bag edges and outside tie edges, the sticker covering the tie intermediate the margins.
7. A bag having when open a rectangular sectional contour creased for folding flat with the short sides adapted to fold inward between the long sides, a metal tie fastened on the outside of one of the long sides near the open end thereof and having side portions and a cross connection between the side portions, the side portions extending parallel and near the outside edges of the long side and a sticker holding the insert to the bag.
8. A bag having when open a rectangular sectional contour creased for folding flat with the short sides adapted to fold inward between the long sides, a metal tie fastened on the outside of one of the long sides near the open end thereof and having side portions and a cross connection between the side portions, the side portions extending parallel and near the outside edges of the long side and a sticker holding the tie to the bag, the bag having one long side recessed at its open end as compared to the end of the other, the recess being upon the side of the tie.
9. A bag having when open a rectangular sectional contour and long sides and short sides creased for adaptation to fold the short sides in between the long sides, a metal tie having side portions along the edges of the long sides near the open ends of the bag and a sticker over the tie having end portions extending beyond the tie sides and fastening to the short sides of the bag.
10. A bag of rectangular contour when open and having long sides and short sides with open ends, a metal rectangular tie upon one of the long sides near the open end thereof and a sticker and margins above and below the tie and gluing to the paper along the margins and in the interior of the tie.
11. A bag, a metal tie outside the top of the bag, extending substantially from side to side of the bag when the bag is closed, and longitudinally of the bag at the sides to an extent permitting the tie to be folded with the bag and fastening means for the tie engaging the bag and permanently holding the tie to the bag.
